COLLECTING AND SEPARATING APPARATUS

Claude B. Schneible and Alvin S. Lundy, Detroit,
Mich.; said Lundy assignor to said Schneible

Application March 23, 1946, Serial No. 656,737

11 Claims. (Cl. 183—79)

1

This invention relates to collecting and separating apparatus. It is particularly useful in the separation of particles from a fluid medium, in the removing of heavier fluids from lighter fluids, and in the removal of such materials as dust, sand particles, chips from castings, and other particles produced in foundries, mills, etc.

An object of the invention is to provide means for removing particles or heavier fluid portions from a fluid stream moving at high velocity through a duct. Yet another object is to provide in a structure for the removal of particles and heavy fluid portions carried in a fluid body moving at relatively high velocity, means for reducing frictional resistance in the separating area and for reducing the back pressure incident to the opening being free in the separation area. Yet another object is to provide in combination with a closed separation chamber, an angular separation duct having an opening in the duct at the outer wall of the bend, means for closing off part of the separating area to reduce frictional resistance and to bring about a more efficient removal of particles or heavy fluid portions. Yet another object is to provide a high velocity duct with an elbow portion communicating through an opening in the heel with a closed chamber, means being provided for closing off a part of the opening in the separating area for reducing frictional resistance and for increasing the effectiveness of the separating means. Other specific objects and advantages will appear as the specification proceeds.

The invention is illustrated, in a preferred embodiment, by the accompanying drawing, in which—

Figure 1 is a transverse sectional view of one form of apparatus embodying our invention; Fig. 2, a broken detail sectional view, the section being taken as indicated at line 2 of Fig. 1; Fig. 3, a view similar to Fig. 2, but showing a slight variation in the shape of the rods employed; Fig. 4, a view similar to Fig. 2, but showing a modified form of the invention; and, Fig. 5, a view similar to Fig. 2, but showing a further modified form of the invention.

In the illustration given, 10 designates a casing which provides a separation chamber 11. The casing may be of any suitable shape or construction as, for example, it may be of the shape indicated in the co-pending application of Claude B. Schneible, Serial No. 656,736, filed March 23, 1946, for Collecting and separating apparatus. It is sufficient that the casing 10 provide a closed chamber of any desired shape which will serve to

2

collect the particles or materials discharged thereinto. The casing 10 is provided with two openings 12 and 13 which may be of rectangular shape or any other suitable shape.

5 A high velocity duct 14, having an inlet portion 15 and an outlet portion 16 and a bend or elbow portion 17, extends through the chamber 11. Preferably, the ends of the duct 14 are provided with flanges which are welded to the casing 10. Any suitable means for producing a high velocity flow of fluid through the duct 14 may be employed. For example, a fan (not shown) may be connected to a duct communicating with the outlet portion 16 of duct 14.

10 The elbow 17 of duct 14 has its outer heel portion cut away to provide an opening and the opening is partially closed by a plurality of rods 18 which extend longitudinally of the heel or elbow. The rods 18 may extend entirely across the opening or they may be welded at one end to the edge 19 of the duct wall 14 and the opposite end of the rods 18 may terminate slightly short of the opposite end of the casing wall 14, thus leaving a gap 20 between the rod 18 and the adjacent wall of the duct 14. As shown more clearly in Fig. 2, the rods 18 are spaced apart and provide therebetween air flow passages 21. The air passage adjacent each row of rods 18 is preferably rectangular in cross section and of very little depth so that the particles within the area can be readily removed through the spaces 21 between rods 18.

15 If desired, the elbow 17 may be provided with a single series of rods extending across a single opening in the heel portion of the duct 14. However, if desired, a plurality of partitions 22 may be supported within the duct 14 so as to divide the interior of the duct into a plurality of separate narrow passages, preferably of rectangular cross section. In the illustration given, each partition 22 is folded upon itself to provide an inner wall 23 and an outer wall 24. The outer wall 24 is imperforate and provides between it and wall 23 a discharge chamber 25 which communicates at its bottom with the chamber 11. The inner wall 23 provides a closed passage for the flow of fluid except at its heel portion which is cut away and provided with spaced rods 18, the rods being positioned as illustrated in Fig. 2. The rods 18 may extend entirely across the openings or may terminate, leaving a short gap 20 between the rods and the adjacent partition wall 22. The gap 20 is of value where stringy material engages the rods and moves longitudinally thereof. Such material is permitted to es-

cape into the chamber 25 or into the chamber 11 by means of the gaps 20.

Instead of employing circular rods 18, as illustrated in Fig. 2, the rods may be given the tear-drop design or shape illustrated in Fig. 3. Such rods 18a of the tear-drop design, as illustrated in Fig. 3, provide effective flow passages 26 therebetween through which the particles and heavier fluid may escape while, at the same time, reducing the inner surface that might engage the particles and cause them to rebound into the passage. It will be noted that the passage 26, as well as passage 21, provides, in effect, a Venturi passage which is highly effective in the removal of particles from the passage while retaining the lighter portion of the fluid within the passage.

In the modification illustrated in Fig. 4, we provide the rods 27 with inwardly extending webs 28 which divide the passage into compartments for straightening the air currents. By thus reducing turbulence and straightening the air currents, we find that highly effective separation is brought about.

In the modification illustrated in Fig. 5, the rods 29 are arranged in staggered relation with the rods 30, and the rods 30 are provided with inwardly extending partition walls 31 serving to straighten partially the air currents.

It will be understood that a great variety of rods and fins or partition walls may be employed for enhancing or increasing the separation effect and to meet the requirements of different types of material which are to be handled.

Operation

In the operation of the structure, fluid is drawn at high velocity through the duct 14 and discharged through the outlet 16 of the duct. The change of direction of the air current causes the heavy particles to continue toward the cut-away heel portions and here the rods are effective in the separation of the particles or heavier fluid while, at the same time, greatly reducing the frictional resistance or back pressure which would otherwise be present. Further, the rods, etc., are effective in maintaining particles, etc., which have already escaped in the chamber 11 from finding their way back into the duct 14. The vanes or partitions 31 or 28 which terminate a short distance from the wall 24 are effective in reducing turbulence and straightening the air currents so that the heavier particles or fluid portions are thrown outwardly and discharged in the chamber 11 while the lighter portions of the fluid pass readily on and out through the opening 16.

We have found that excellent results are produced where the cut away heel portion or separating area is reduced by 50% or more through the use of the rods, etc. The multiple rod bank illustrated in Fig. 5 is highly effective for the handling of certain materials where it is desired to retain the mass of the lighter fluid within the duct and to obtain a relatively fine separation of the particles or heavier fluid carried within the duct. The vanes or partition walls not only are effective in straightening air currents but also serve as guides or deflectors which tend to bring the heavy particles toward the discharge openings and to insure their removal from the passage.

In referring to the separation chamber as a closed or air-tight chamber, it will be understood that the terms are used in their broad meaning and that the separation chamber may, in fact,

communicate with another chamber or passage which in turn is closed by virtue of its being connected with a closed system. It will also be understood that the separation passages herein described as a multiple arrangement may, if desired, be a single passage or single conduit having a single heel portion cut away and provided with rods and vanes of the type herein illustrated or other suitable types. The passages are preferably of thin rectangular cross section and the bend or elbow may extend in any direction including the horizontal, vertical and other angular positions. The rods which are shown running longitudinally of the opening may, if desired, be inclined to run in an oblique or other desired angular positions, such positions being herein referred to by the term "longitudinal."

While in the foregoing description, we have set forth in substantial detail structures with which the invention may be employed, it will be understood that such details of the structures may be varied widely by those skilled in the art without departing from the spirit of our invention.

We claim:

- 25 1. In combination, a casing providing a closed separation chamber, a high velocity fluid duct having an elbow bend and with a cut away heel portion communicating with said chamber, and a plurality of curvilinear rods extending longitudinally of said opening in laterally-spaced-apart relation and providing spaced passages extending longitudinally of said elbow portion between said duct and chamber.
- 30 2. In combination, a casing providing a closed separation chamber, a high velocity fluid duct having an elbow bend and with a cut away heel portion communicating with said chamber, and a plurality of curvilinear rods extending longitudinally of said opening in laterally-spaced-apart relation and providing spaced passages extending longitudinally of said elbow portion between said duct and chamber, said rods being of generally round cross section.
- 35 3. In combination, a casing providing a closed separation chamber, a high velocity fluid duct having an elbow bend and with a cut away heel portion communicating with said chamber, and a plurality of curvilinear vanes extending longitudinally of said duct in laterally spaced-apart relation adjacent said opening.
- 40 4. In combination, a casing providing a closed separation chamber, a high velocity fluid duct having an elbow bend and with a cut away heel portion communicating with said chamber, a plurality of curvilinear rods extending longitudinally of said opening in laterally spaced-apart relation, and a plurality of vanes leading from said rods inwardly into said duct.
- 45 5. In combination, a casing providing a closed separation chamber, a high velocity fluid duct having an elbow bend and with a cut away heel portion communicating with said chamber, a plurality of curvilinear rods extending longitudinally of said opening in laterally spaced-apart relation, and a plurality of vanes extending inwardly from said rods and across said duct to divide said duct into a plurality of compartments adjacent said heel.
- 50 6. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing
- 55 7. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing
- 60 8. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing
- 65 9. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing
- 70 10. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing
- 75 11. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing

spaced tortuous passages between said duct and said chamber.

7. In combination, a casing providing a closed separation chamber, a high velocity fluid duct having an elbow bend and with a cut away heel portion communicating with said chamber, and a plurality of curvilinear rods arranged in a plurality of series extending in staggered relation longitudinally of said opening and providing spaced tortuous passages between said duct and said chamber, certain of said rods being provided with inwardly extending vanes entering said duct.

8. In combination, a casing providing a separation chamber, a fluid duct having an elbow bend provided with a heel portion that is cut away to provide an opening substantially equal to the length of the elbow communicating with said chamber, and a plurality of rods circular in cross-section and curved throughout their length extending longitudinally of said opening in laterally spaced-apart relation to provide longitudinal passages extending substantially the length of the elbow bend, said rods proving Venturi passages between them.

9. In combination, a casing providing a closed separation chamber, a fluid duct having an elbow bend and with a cut-away heel portion communicating with said chamber, and a plurality of curvilinear rods extending longitudinally of said opening in laterally spaced-apart relation and providing spaced passages extending longitudinally of said elbow portion, said rods being of teardrop shape in cross section.

10. In combination, a casing providing a separation chamber, a fluid duct having an elbow which is of elongated rectangular shape in cross section and with a cut-away heel portion communicating with said chamber, and a plurality of spaced members fixed to said duct at one end

of said heel portion and extending across said opening to provide spaced passages between said duct and chamber, said members having free ends terminating short of the other end of the opening to provide a gap between said free ends and the duct casing at said other end of the opening.

11. In combination, a casing providing a separation chamber, a casing providing a fluid duct having an elbow with a cut-away heel portion communicating with said chamber, and a plurality of rods fixed to said duct casing at one end of the heel opening and extending longitudinally across said opening, said rods having free ends terminating short of the other end of said opening to provide a gap between said free ends and the duct casing at said other end of the opening.
